UNITED STATES PATENT OFFICE.

CHARLES C. WORTHINGTON, OF DUNNFIELD, NEW JERSEY.

TEE STAND.

Application filed June 21, 1923. Serial No. 646,773.

To all whom it may concern:

Be it known that I, CHARLES C. WORTHINGTON, United States citizen, residing at Dunnfield, county of Warren, and State of New Jersey, have invented the following described Improvements in Tee Stands.

The object of the invention is to provide a structure of pleasing appearance and rugged and practical design for supporting the sand and water buckets and other devices used at the driving tees of golf courses, and the invention consists in the shape, relative arrangement and manner of connection of the several parts of the stand, as herein-
10 after disclosed and more particularly pointed out in the appended claims.

In the accompanying drawing, Fig. 1 is a side elevation;

Fig. 2 a front elevation; and

Fig. 3 a top plan of the tee stand in its preferred form.

The stand comprises a main easel-type frame formed by one or more lengths of metal rod or piping bent or assembled into the shape of a flat, inverted U, preferably with an arch or curved top bar 1. The side limbs 2 of this frame are joined about midway between top and bottom by a cross-structure which serves the two functions of 20 bracing the frame and supporting the sand or the sand bucket 3. It may be variously formed for this purpose but is preferably constituted of two equal pieces of strap iron 4 united at their point of connection 25 with the limbs and spaced apart at their center to form a bucket-receiving ring. The sand bucket 3 set in this ring, is held rigid with respect to the frame, and also symmetrical to the frame, that is to say, the 30 strap pieces 4 are duplicates of each other and the center of the ring and also the center of the sand bucket are therefore situated substantially in the plane of the flat U frame, or at least so that said plane intersects the bucket. The latter is desirably removable from the ring or cross structure. The ends of the straps 4 are joined to the 40 frame limbs 2, by means of the two fittings 5, one on each limb, which fittings also provide attachment sockets for the rear leg structure 6. The rear legs, of which there are preferably two, one for each limb, hold the flat U frame at an inclination from horizontal of about 60° and are themselves 50 inclined at about the same angle. The frame limbs and the legs are also respec-

tively convergent towards each other and this arrangement provides a wide supporting base with the center of gravity of the stand quite near its center, thus providing adequate stability. The two legs 6 are joined and braced by a cross rod 7 and the lower parts of the frame limbs 2 are similarly braced by a cross rod 8, but no cross rod or other connection extends between the rear legs and the front lower part of the frame so that this space is left open and the ground under the buckets is thus easily accessible with a rake for the removal of trash.

The fittings 5 may be formed as sleeves slipped over the limbs 2 before the cross rods 8 are riveted in place, and in this case they are provided with set screws, as illustrated, to secure them in position, being thereby rendered adjustable to a certain extent so that the legs can be raised and lowered on the frame to accommodate the stand to a sloping ground surface. The rear legs are removably secured in the inclined sockets of fittings 5 by cross pins locked by split cotter.

The water container 9 is an ordinary bucket with or without a pouring spout and is provided with a pivoted bail handle by 85 which it is hung to the hook fixed to the top bar of the U frame, or otherwise secured to the frame, so that it can be tipped forwardly to pour water into the sand bucket. For the sake of appearance the top bar of 90 the U frame is curved to the same center as the bail of the water bucket. On one side of the frame there is mounted a golf ball cleaner 10 and on the opposite side a mousing hook to hold a towel.

While the construction of the stand according to this invention is subject to considerable variation in structural detail, it may be noted that the two side limbs and the curved top bar occupy the same plane 100 and that the slant of the flat frame thus formed is so proportioned to its length that an ordinary bail handled water bucket, such as 9, hung directly below the top bar will pour and also drip directly into the symmetrically located sand bucket when tilted forwardly, and about as indicated in the dotted lines of Fig. 1 and this arrangement is important, since it is desirable that it be made easy to pour a small closely regulated 105 amount of water into the sand without splashing or wasting water. At the same

time the inclination and easel effect of the main frame gives the stand a distinctive and artistic appearance. The support of the inclined frame by inclined legs, connecting therewith at a point near its middle, adds to the pleasing effect, although it will be obvious that the main frame might be otherwise supported at the same inclination. The formation of the side limbs and top bar all in the same plane, and the removability therefrom of the rear legs, afford obvious conveniences of manufacture and a special convenience in respect of transportation, since the legs and frame can be separated and packed flat, making a compact package for shipment, the subsequent process of assembly being very easily done by merely inserting the legs and pinning them in their sockets.

Having described my invention, I claim the following:

1. A tee stand comprising a flat easel frame provided with means for supporting it in an inclined position, means for holding a tipping water bucket at the top of the frame and a sand-containing structure joining the side limbs of the frame about midway of its top and bottom in a position to receive water from the bucket when tilted.
2. A tee stand comprising a flat easel frame provided with means for supporting it in an inclined position, a sand containing structure joining the side limbs of the frame, and situated thereon with its center substantially coincident with the plane of the inclined frame and about midway of the top and bottom thereof and a tipping water bucket supported on the upper part of the frame to pour into the sand when tipped.
3. A tee stand comprising a flat easel frame supported in an inclined position and formed of convergent side limbs united by a sand containing structure at a mid point of the frame, and a tipping water bucket suspended from the upper part of the frame to pour into the sand when tipped.
4. A tee stand comprising an inclined, flat frame, inclined means for supporting the same in its inclined position, joined thereto at about its middle, a sand-containing cross structure secured to the frame at the junction of the supporting means therewith, and a water bucket suspended from the upper part of said inclined frame to discharge into said structure.
5. A tee stand comprising a frame composed of two side limbs, a sand-containing cross structure uniting the same, rear legs supporting said parts, the side limbs above said structure being inclined rearwardly and joined by a cross part over said legs and a water bucket suspended from said cross part

to pour into the sand-containing structure when tipped.

6. A tee stand comprising a flat inverted ⁶⁵ U frame, means for supporting it in an inclined position, a tipping water bucket suspended from the top bar of the U frame, and a sand-containing structure joining the side limbs of the frame near its middle.

7. A tee stand comprising a flat U-frame, fittings thereon, inclined rear legs removably engaged to the fittings and supporting the frame in an inclined position, a sand container supported on the fittings, and a water bucket supported on the upper part of the frame to pour into said container.

8. A tee stand comprising a flat frame having side limbs, inclined rear legs and adjustable fittings on said limbs attached to the legs and supporting the frame in an inclined position, a sand container connected to the frame between the fittings and a water bucket suspended from the top of the frame to pour into the sand container.

9. A tee stand comprising a flat inverted U frame, a cross structure joining the side limbs of the frame near the middle thereof, a sand bucket removably held by said structure, a water bucket suspended from the top bar of the U to pour into the sand bucket when tipped and rear legs supporting said U frame in an inclined position.

10. A tee stand comprising a U frame, provided with means for supporting it in an inclined position, a sand bucket supporting structure rigidly joining the side limbs of said frame and comprising equal straps spread apart to form a bucket ring, a sand bucket seated in said ring and a tipping water bucket supported on the upper part of said U frame to pour into the sand bucket when tipped.

11. A tee stand comprising a flat U frame a sand-containing structure uniting the side limbs thereof, with its center substantially coincident with the plane of the frame, inclined rear legs supporting said limbs in an inclined position and a bail-handled water bucket hung on the upper part of the frame to pour into the sand container when tipped.

12. A tee stand comprising a flat, inverted U-shaped frame, fittings thereon, a sand bucket supporting structure joining the fittings, rear inclined legs attached to the fittings and supporting the frame in an inclined position and a bail-handled water bucket hung from the top of the U and adapted to pour into the sand bucket when tipped.

In testimony whereof, I have signed this specification.

CHARLES C. WORTHINGTON.
